UNITED STATES PATENT OFFICE

2,366,244

HATPIN

Jack I. Ellerstein, New York, N. Y.

Original application May 15, 1942, Serial No. 443,084. Divided and this application January 16, 1943, Serial No. 472,545.

2 Claims.

(Cl. 24—150)

This invention is a division of my application Serial No. 443,084, filed May 15, 1942 which has matured into Patent No. 2,317,746, granted April 27, 1943, for hat pins.

In one form, the invention proposes a hat pin in which a rigid sheet material base, such as a piece of cardboard or the like, is mounted or held upon the blunt end of a hat pin shank, preferably with a staple, and in which plastic material such as plaster of Paris covers the said holding means and rigid sheet material and forms a base for receiving surface ornamentation.

In another form, the invention proposes the construction of hat pins which are characterized by hat pin shanks each having a blunt end and a pointed end, and heads of plastic material mounted on the blunt ends, and in certain forms provided with surface ornamentation.

It is particularly proposed that the heads of the hat pins be made of flat forms and of different shapes, for artistic purposes. It is furthermore proposed that they be of various colors and suitably provided with surface ornamentation, when desired.

Still further it is proposed that the heads of the hat pins be formed by suitable molds and dies, not disclosed in this specification.

Another object of the invention resides in a construction of a hat pin in which the shank is removably connected with the head.

Another object of the invention is the construction of articles as described which are simple and durable and which may be manufactured and sold at a reasonable cost.

For further comprehension of the invention, and of the objects and advantages thereof, reference will be had to the following description and accompanying drawings, and to the appended claims in which the various novel features of the invention are more particularly set forth:

In the accompanying drawings forming a material part of this disclosure:

Fig. 1 is a perspective view of a hat pin constructed in accordance with one form of this invention.

Fig. 2 is an elevational view of the rigid sheet material and the hat pin shank of the hat pin shown in Fig. 1.

Fig. 3 is an enlarged sectional view taken on the line 3—3 of Fig. 1.

Fig. 4 is an elevational view of another hat pin embodying another form of this invention.

Fig. 5 is a fragmentary sectional view taken on the line 5—5 of Fig. 4.

Fig. 6 is a perspective view of another hat pin embodying another form of the invention.

Fig. 7 is a sectional view taken on the line 7—7 of Fig. 6.

Fig. 8 is a perspective view of a hat pin constructed in accordance with another form of this invention.

Fig. 9 is a fragmentary sectional view through the top portion of the hat pin shown in Fig. 8.

Fig. 10 is a perspective view of a hat pin constructed in accordance with another form of this invention.

Fig. 11 is a fragmentary elevational view of a hat pin constructed in accordance with still another modification of this invention.

Fig. 12 is a fragmentary enlarged sectional view of the hat pin shown in Fig. 11, but illustrated with the shank and head separated.

Fig. 13 is a perspective view of another hat pin embodying another form of this invention.

Fig. 14 is a fragmentary enlarged sectional view taken on the line 14—14 of Fig. 13.

It is pointed out that the word "plastic" as used in this specification is used in its broad sense to mean material which can be molded, and to include quite a large group of materials such as phenol condensation products, synthetic resins, plastic woods, and plasters of various types, etc.

30 The new hat pin, in accordance with the form of the invention illustrated in Figs. 1 to 3 comprises a hat pin shank 20 having a back end 21 and a pointed front end 22, with a head 23 mounted on the said back end 21. The head 23

35 comprises a small piece of rigid sheet material 24 mounted upon the said blunt end 21 with a suitable holding element, or means, such as a staple 25, and plastic material 26 covering said holding means 25 and the rigid sheet material 24

40 and suitably ornamented. The rigid sheet material 24 may be of any shape. These pieces can be made in large quantities very inexpensively with rotating dies, generally used to stamp out small cardboard, and the like, pieces. The staple

45 25 may be applied to connect the rigid sheet material 24 to the pin shank 20 with a conventional staple applying, or stapling machine. It will be found that the machines generally used for stapling are capable of securely connecting the rigid sheet material 24 with the pin shank 20 so that they cannot be easily drawn apart.

The plastic material 26 may be applied with a blow gun, or by dipping. It may be plaster of Paris or other material useful for filling and covering, a staple or clip 25, and the blunt end 21

of the pin shank to conceal these parts. The surface ornamentation which is applied upon the plastic material 26 may comprise flock 27, or lacquer or other covering materials.

The modified form shown in Figs. 4 and 5 discloses a hat pin which has a hat pin shank 20 having a back end 21' and a pointed front end 22. A shell 28" is mounted upon the said back end 21' of the pin shank. This shell 28" is formed from a pair of shell sections 29" and 30" which are set one into the other. These shell sections have face walls and skirt walls. The skirt walls are interengaged one into the other. The back end 21' of the pin shank 20 is bent into circular form so as to extend along the inner skirt wall portion of the inner shell of the shell sections. The shell 28" is shown to be round. The bend end 21' is similarly formed and serves to firmly support the back end 21' of the said pin shank 20. At one point the skirt walls of the shell sections are formed with openings 31 through which the pin shank 20 extends.

In Figs. 6 and 7 still another form of the invention is disclosed in which the hat pin comprises a small piece of rigid material 35 such as cardboard, wood, a plastic or the like, and a pin shank 36. This pin shank has a pointed back end 37 which is stuck into the edge of the material 35. The pin shank 36 also has a pointed front end 38. Surface ornamentation 39 is applied to the exterior of the material 35 and may comprise flock, lacquer or the like.

The hat pin, in accordance with the form of the invention shown in Figs. 8 and 9, includes a hat pin shank 20 having a back blunt end 21 and a front pointed end 22. This shank is constructed of steel in the usual way. A head 23' of plastic material is mounted on the blunt end 21. To facilitate the permanent connection of these parts, the blunt end 21 is formed with a small groove 40 into which the plastic material of the head 23' engaged during the time that the plastic head was molded on the blunt end of the shank. The blunt end 21 is also knurled.

The head 23' is shown of flat design and of a trapezoidal shape. The plastic material may be suitably colored and if desired, surface ornamentation also added.

In Fig. 10 another embodiment of the same invention is disclosed in which the head 23a is flat and of circular shape. In other respects this form of the invention is identical to the previous form and like parts are indicated by like reference numerals.

In Figs. 11 and 12 still another form of the invention has been disclosed which is very similar to the form shown in Figs. 8 and 9, distinguishing merely in the fact that the shank 20b is removably connected with the head 23b. This is accomplished by providing the head 23b with a shell 45 which is embedded therein. The shell 45 has a closed inner end 46 and an open outer end. It is also provided with a plurality of side openings 47 into which the plastic material of the head is engaged for permanently mounting the shell therein. A tube 48 is fixedly mounted in the shell 45. It is held in position by an inturned edge portion 49 formed on the outer end of the shell 45. The shell is set into one side of the head 23b.

The tube 48 is provided with several inwardly bent perforated portions 50 forming resilient sections. These resilient sections are adapted to engage and grip the groove 40 formed on the blunt end 21b of the shank 20b. The blunt end of the shank is also formed with a small end bevel 51 to facilitate its engagement into the tube 48. The shank 20b may be engaged into the tube 48 and will then be held by the resilient sections 50, and when desired, it may be pulled out.

In the form of the invention illustrated in Figs. 13 and 14 the hat pin includes a hat pin shank 20 having a back end 21 and a pointed front end 22. A head 23" is mounted on the back end 21. This head includes a small piece of cardboard 24 mounted on the said back end 21 with a suitable holding element, such as the staple 25. A ribbon bow 52 covers the cardboard 24, the staple 25 and said back end 21 of the pin shank 20. The bow 52 is formed from a strip of ribbon 53 which is zigzagged back and forth to form the wings of the bow, and a band 54 which is mounted around the center of the wings. This band 54 is made from a strip and is mounted in place while it is still open. It is first engaged on the pin shank 20. Then the cardboard 24 is placed between the layers of the ribbon 53. The band 54 is then engaged around the central portion of the wings of the ribbon, and then is secured in position with stitches 55.

While I have illustrated and described the preferred embodiments of my invention, it is to be understood that I do not limit myself to the precise constructions herein disclosed and the right is reserved to all changes and modifications coming within the scope of the invention as defined in the appended claims.

Having thus described my invention, what I claim as new and desire to secure by United States Letters Patent is:

1. A hat pin, comprising a hat pin shank having a pointed front end and a straight central portion and a coiled back end, a shell section having a flat front wall extending across one face of said coiled back end and having a skirt wall extending around the edge of said coiled back end and said skirt wall having an opening through which said straight central portion extends, and another shell section having a flat back wall extending across the other face of said coiled back end and also having a skirt wall mounted on said first named skirt wall and said second named skirt wall having an opening through which said straight central portion extends.

2. A hat pin, comprising a shell having a skirt wall portion having an opening at one point, a hat pin shank having a pointed front end and a back end extending through said opening into said shell, and means within said shell and connected with said back end of said pin shank and engaging the inner faces of said shell for supporting said pin shank, said shell including a pair of shell sections having face walls and skirt walls, said skirt walls engaging one into the other and forming said skirt wall portion.

JACK I. ELLERSTEIN.
